UNITED STATES PATENT OFFICE.

HERMAN E. CROME, OF JERSEY CITY, NEW JERSEY.

DRIP-PAN FOR PAINTING METAL FURNITURE.

SPECIFICATION forming part of Letters Patent No. 707,087, dated August 19, 1902.

Application filed May 17, 1902. Serial No. 107,716. (No model.)

To all whom it may concern:

Be it known that I, HERMAN E. CROME, a citizen of the United States, residing at Jersey City, in the county of Hudson and State of New Jersey, have invented certain new and useful Improvements in Drip-Pans for Painting Metal Furniture, of which the following is a full and complete specification, such as will enable those skilled in the art to which it applies to make and use the same.

The object of this invention is to provide an improved drip-pan for use in painting parts of metal bedsteads, couches, and other articles of furniture made of metal, a further object being to provide an improved device or apparatus of this class by means of which the parts of a bedstead or other article of furniture may be agitated or moved in the paint, so as to cause the paint to thoroughly cover the same and by means of which the surplus paint may be partially drained from the article before the latter is removed from the pan and by means of which the paint when used may be strained, so as to remove therefrom dirt, scales, and other substances in order that the paint may be reused; and with these and other objects in view the invention consists in a drip-pan for painting articles of furniture or parts thereof, constructed as hereinabove described and claimed.

The invention is fully disclosed in the following specification, of which the accompanying drawings form a part, in which the separate parts of my improvement are designated by suitable reference characters in each of the views, and in which—

Figure 1 is a plan view of my improved drip-pan; Fig. 2, a longitudinal section on the line 2 2 of Fig. 1; and Fig. 3, a cross-section on the line 3 3 of Fig. 1.

In the practice of my invention I provide a drip-pan of the class specified, which is oblong and rectangular in form and which is open at the top and composed of two parts a and a^2 , said parts being adapted to be separated by a removable screen b , held in place when in use by vertically-arranged keepers b^2 . The part a is preferably longer than the part a^2 and is adapted to rest in the horizontal position on any suitable support, while the part a^2 is upwardly inclined, as clearly shown in Fig. 2, the extent of this inclination

at its greatest point being preferably about equal to the depth of the pan, and the side and end walls of the pan; including both parts 55 thereof, are preferably flared outwardly, as shown at a^3 .

Placed transversely in the bottom of the part a and adjacent to the keepers b^2 is a shaft c , held in place by keepers c^2 and c^3 , secured to the bottom of the part a , and this shaft is provided with a crank c^4 , and secured to said shaft is a perforated plate d , which is adapted to normally rest on the bottom of the part a and which is preferably substantially 65 of the same length as the said bottom of the part a and the end of which, opposite the shaft c , is preferably cut out to form a recess, as shown at d^2 , and said plate d is provided near the end thereof which is secured 70 to the shaft c with a transverse bracket or support e . By means of the crank c^4 of the shaft c the plate d may be raised into an upright position, as indicated in dotted lines in Fig. 2, when the screen b is not in position, and in practice paint is placed in the pan or in the part a thereof and said pan or said part is partially filled with said paint, and whenever it is desired to paint the head-frame or foot-frame of a metal bedstead or 80 any other article of furniture or part thereof the said article of furniture or part thereof is placed on the plate d to the right of the bracket or support e , and the said plate is raised and lowered or agitated in the paint 85 by means of the crank c^4 , and when the said article is thoroughly covered with the paint the plate d is raised to the position indicated in dotted lines in Fig. 2, and the surplus paint flows from the article of furniture back into 90 the pan, and the said article of furniture is removed from the plate d by a crane and conveyed to a drier or driers in the usual manner. When the plate d is raised into an upright position, as indicated in dotted lines in 95 Fig. 2, the article of furniture thereon rests on the support or bracket e , and said plate is not raised exactly vertical, but is held at a slight inclination, and the article of furniture is supported in an upright or partially-upright position until removed, as above described.

It will be understood that in the above-described operation the screen b is not in use,

and in the operation of painting an article of furniture or parts thereof when the paint becomes more or less foul by means of scales and other dirt or substances which collect 5 therein, and at the close of a day's work or at any other time the end *a* of the pan may be raised so that most of the paint therein will flow into the end *a*², and the screen *b* may then be placed in position and the end *a* of 10 the pan lowered into its normal position, and the paint will flow back through said screen into the part *a* of the pan, and the scales, dirt, and other substances will be retained in the part *a*² and may be removed therefrom.

15 This device is simple in construction and operation and comparatively inexpensive, and by means thereof articles of furniture of the class specified or parts thereof may be quickly and easily painted, and a much less waste of 20 time and at a much less expense than by means of the apparatus and processes now employed.

From the foregoing description it will be observed that the plate *d* serves as an elevator to lift the article of furniture out of the 25 paint or out of the paint-pan, and this avoids the necessity of the attendant grasping said article by the hand in order to lift it from the vat or pan, and when the article has once been raised into an upright or partially-up- 30 right position it may be removed by a crane, as hereinbefore stated, without in any way disturbing the paint or enamel thereon.

Having thus fully described my invention, what I claim as new, and desire to secure by 35 Letters Patent, is—

1. A drip-pan for painting articles of furniture or parts thereof, said pan comprising two parts one of which is adapted to rest in a horizontal position and the other of which is 40 normally held in a raised or inclined position, a shaft mounted transversely of said pan and in the end of the horizontal portion thereof adjacent to the other portion thereof, and a perforated plate connected with said 45 shaft and adapted to rest on the bottom of the horizontal portion thereof, substantially as shown and described.

2. A drip-pan for painting articles of furniture or parts thereof, said pan comprising 50 two parts one of which is adapted to rest in a horizontal position and the other of which is

normally held in a raised or inclined position, a shaft mounted transversely of said pan and in the end of the horizontal portion thereof adjacent to the other portion thereof, 55 and a perforated plate connected with said shaft and adapted to rest on the bottom of the horizontal portion thereof, and said plate being provided near said shaft with a bracket or support, substantially as shown and de- 60 scribed.

3. A drip-pan for painting articles of furniture or parts thereof, said pan comprising two parts one of which is adapted to rest in a horizontal position and the other of which is 65 normally held in a raised or inclined position a shaft mounted transversely of said pan and in the end of the horizontal portion thereof adjacent to the other portion thereof, and a perforated plate connected with said 70 shaft and adapted to rest on the bottom of the horizontal portion thereof, and said plate being provided near said shaft with a bracket or support, and said pan being provided adjacent to said shaft with a transverse screen, 75 substantially as shown and described.

4. A drip-pan for use in painting articles of furniture or parts thereof, said pan being oblong in form and composed of two parts, one of which rests in a horizontal position and 80 the other of which is held in a raised or inclined position the transverse screen mounted in said pan at the junction of the two parts, a shaft transversely mounted in said pan adjacent to said screen and provided with a perforated plate which is secured thereto and adapted to normally rest on the bottom of the horizontal part of the pan, said plate being provided adjacent to said shaft with a trans- 85 verse bracket and at the opposite end there- 90 of with a recess, and said shaft being provided with a crank, substantially as shown and described.

In testimony that I claim the foregoing as my invention I have signed my name, in presence of the subscribing witnesses, this 15th day of May, 1902.

HERMAN E. CROME.
